UNITED STATES PATENT OFFICE

2,565,724

PERSPECTIVE DRAFTING MACHINE

Clair C. Foster, Seattle, Wash., assignor to Boeing
Airplane Company, a corporation of Delaware

Application February 5, 1945, Serial No. 576,289

13 Claims. (Cl. 33—77)

1

Drafting machines providing a guide or straightedge for drawing lines in parallel relationship at various locations on a drafting table are employed customarily. The present invention is directed to a similar type of machine, but it incorporates a guide for drawing at various locations on a drafting board lines directed toward a selected vanishing point, instead of being parallel. Such lines are present in a true perspective drawing.

The principal object of my invention, therefore, is to provide control mechanism for a guide which will alter the angularity of the guide as it is moved bodily over a drafting table so that the guide will always be in alignment with a selected vanishing point.

A further object of my invention is to provide such mechanism which will enable the guide to be shifted over a large area of the drafting table. Nevertheless the device is of simple construction, and incorporates a minimum of operating parts.

It is also an object to provide such a drafting machine which can be adjusted readily for the purpose of directing the guide toward a vanishing point at a different location.

Still another object of my invention is to enable the guide to be mounted selectively on the drafting machine in either of two positions, enabling one or the other of its edges to be used as the line guide at will.

Other features of my perspective drafting machine will be pointed out in the following description of a preferred form of the device.

Figure 1 is a plan view of my perspective drafting machine, portions of it being broken away. Figure 2 is a side elevational view of the machine with corresponding portions broken away, the interconnected links all being aligned in vertical registry instead of being disposed in intersecting positions as shown in Figure 1.

Figure 3 is a transverse sectional view through one portion of the machine, taken on line 3—3 of Figure 2. Figure 4 is a horizontal sectional view through the same portion of the machine on line 4—4 of Figure 3.

The machine is supported from a base plate 1 which may be attached in any convenient location to the edge of the drafting table. A normally stationary mounting arm 10 is supported by a pivot 11 on the base plate 1 for swinging relative to it. One end of the arm carries a circular section 12, which conveniently may be integral with it, the arc of which has its center at the axis of pivot 11. This sector preferably has an

extent of approximately 180 degrees, and may constitute a protractor head. Locking mechanism is provided for the sector, which may be a clamping washer 13 capable of being forced downward into gripping engagement with the sector or head to press it against the base plate 1 by screwing down a wing nut 14 threaded on a bolt upstanding from the base plate alongside the periphery of the sector. When the sector is thus secured arm 10 will be held stationary.

A guide or straightedge 2 is supported by a web 20 from a bracket 21 which is carried by a swingable arm 22. This arm is pivotally connected to an auxiliary link 23 of fixed length by a pivot 24. The other end of this link is joined by a pivot 25 to a control link 3 interconnecting the normally fixed mounting arm 10, arm 22 and link 23. This control link is swingable relative to arm 10 about the normally stationary pivot 30 which interconnects them, and a pivot formed by blocks 31 swingable about a stationary bolt 34 guides control link 3 and arm 22 for swinging relative to each other as the guide 2 is moved over the drafting table.

Control mechanism is provided to correlate the movement of link 23 with arm 10. It includes pulleys 26 and 15, respectively, mounted concentrically with pivots 25 and 30, which are interconnected by a control cable 32 engaging such pulleys positively to maintain them always in corresponding rotative positions. The cable may be drawn sufficiently taut to insure such coordinated movement by turnbuckle connectors or equivalent tensioning mechanism. Pulley 26 is

fixed to link 23 to rotate with it and pulley 15 is similarly fixed relative to arm 10 so that such link and arm are always maintained in corresponding angular positions. These members are adjusted so that the action of the cable 32 and pulleys 26 and 15 is equivalent to a parallel linkage device, capable of maintaining arm 10 and link 23 continuously in parallel relationship. It will be evident that while these pulleys and interconnecting cable constitute a convenient form

of control mechanism, arm 10 and link 23 might be maintained in parallelism as the link is swung by conventional parallel linkage formed by the addition of a link interconnecting arm 10 and link 23 spaced lengthwise of such arm and link from control link 3 and always parallel to the control link. The essential consideration here is that mechanism of some suitable type be provided to maintain the link parallel to the arm, which mechanism may or may not include control link 3.

As previously stated, the parts of my perspective drafting machine may be adjusted to vary the location of the vanishing point, but it will be convenient to consider first the manner in which the machine operates with the parts in one selected position of adjustment in which they would frequently be used, such, for example, as that illustrated in the drawing. Link 23, the section of control link 3 between it and the pivot axis of blocks 31, and the portion of arm 22 between such pivot axis and pivot 24 form a triangle. Also it may be considered that the line of arm 10 extended beyond pivot 30, the portion of control link 3 intermediate its pivot 30 and the axis of bolt 34, and a line in alignment with arm 22 between the axis of bolt 34 and the line of arm 10 extended form a second triangle. These two triangles are similar. The control mechanism, including pulleys 15 and 26, and cable 32, maintains link 23 parallel to arm 10, making the angle between control link 3 and link 23 equal to the opposite angle between control link 3 and the line of arm 10 extended to the left in Figure 1; also, the angles of these triangles formed by the intersecting control link and arm 22 are equal. It follows, therefore, that the sides of such triangles are proportional.

By virtue of the similarity of the triangles mentioned the ratio between the portions into which link 3 is divided by the axis of bolt 34 will be equal to the ratio between the length of link 23 and the intercept on the line of arm 10 between pivot 30 and the intersection of lines in alignment with arm 10 and arm 22. Through whatever position straightedge 2 may be shifted over the board such intersection will remain stationary since the length of link 23 is fixed. Consequently the intersection of the lines of arms 10 and 22 defines the vanishing point for which the machine is set, toward which straightedge 2 will always be directed, which is the requirement for perspective illustration.

As shown best in Figures 2, link 3 is preferably of double construction, including upper and lower straps or bands between which the pulleys 15 and 26 are received. This control link, in turn, is supported in cantilever fashion by its pivot 30 being mounted in a bracket 16 carried by the end of arm 10. Link 23 and arm 22 are in turn supported by control link 3. It will be evident, therefore, that any angular adjustment in the position of arm 10 about its pivot 11 will carry bodily with it the straightedge control mechanism described. In order to shift the location of the vanishing point angularly about such pivot, therefore, it is merely necessary to loosen wing nut 14 and to rotate sector 12 to the extent desired. This sector may bear a scale graduated in degrees and cooperating with a suitable index mark on base 10, to form a protractor head indicating the angular disposition of arm 10. Alternatively the scale may be provided on the base and the index mark placed on the sector.

Since the two triangles mentioned above are similar, the ratio of the parts into which the axis of bolt 34 divides control link 3 determines the ratio of all sides of the similar triangles. Because the effective length of link 23 is fixed, the spacing between the vanishing point and pivot 30 may be altered by shifting the pivot axis defined by bolt 34 along link 3. A shift of such pivot axis toward arm 10 will move the vanishing point closer to pivot 30, whereas it can be moved away from such pivot by shifting bolt 34

toward link 23. The mechanism enabling such adjustment to be made, is shown best in Figure 3.

5 A saddle or slide 33 is guided for movement along the upper strap of control link 3. This saddle has in it a threaded hole through which bolt 34, about which blocks 31 pivot, may be screwed into endwise engagement with the control link. A locking disk 35 secured to a lock nut and to the bolt may be rotated to effect such clamping action between the link and slide. When it is desired to change the distance between pivot 30 and the vanishing point, disk 35 will be rotated in a direction to release the bolt 34 from the link, whereupon slide 33 may be shifted along the link to any desired degree.

20 A pointer 36, carried by saddle 33 and cooperating with a scale 37 arranged lengthwise of link 3 will indicate the proportionality into which bolt 34 divides the control link. This scale, as shown in Figure 4, may be graduated in units of length representing the distance between pivot 30 and the vanishing point. The divisions of the scale representing a shift of the vanishing point through a unit distance will not be uniform, but, as is evident from Figure 4, the graduations will be increasingly close together toward pivot 25 because of the great change in proportionality which is effected by a slight increase in the 25 angles within the triangles mentioned at opposite sides of the intersection of arm 22 and link 3 as bolt 34 approaches pivot 25.

30 As previously stated, the length of link 23 is always fixed. Also, in any adjusted position of slide 33, the intercept of control link 3 between pivot 25 and the pivot axis of blocks 31 will also be fixed. In order to preserve the proportionality between the sides of the two similar triangles as control link 3 and the straightedge is swung, therefore, the length of arm 22 must change. It is immaterial which end of this arm is movable, or whether both are movable lengthwise of the arm. Since pivot 24 preferably connects one end of arm 22 in definite relationship to link 23, however, the other end of arm 22 must be movable relative to control link 3 to change the effective 40 length of such arm.

45 Preferably arm 22 is formed as a hollow channel member having inturned flanges 27 which are engageable with rollers 38 carried by opposite ends of generally parallel resilient bands 39. These bands are secured centrally to pivot blocks 31 which are recessed to embrace bolt 34. The resilience of such bands both presses the rollers 38 against flanges 27 and also holds the blocks 31 against bolt 34. Such interconnection enables 50 arm 22 to be mounted fully above the composite control link 3, as shown in Figure 2. Moreover the combined lengths of control link 3 and link 23, when they are in alignment, is sufficient to enable straightedge 2 to pass beyond base 1, as shown in Figure 2. The straightedge may therefore be swung freely to either side of the base, its alignment with the vanishing point being 55 maintained by the control mechanism with equal facility at both sides of the base.

60 Preferably bracket 21 is formed as a hinge part complementary to a second hinge part 28 carried by the end of arm 22. These hinge parts are 65 interconnected by a removable bolt 29. Such hinge parts are formed so that when they are assembled as shown in solid lines in Figure 1 the upper edge of straightedge 2 as seen in Fig. 1 will be aligned with the center line of arm 22. 70 If bolt 29 is removed and bracket 21 is shifted to

assemble its hinge part in the opposite eccentric position with hinge part 28 the straightedge 2 will be disposed in the broken line position shown in Figure 1 with its lower edge in that figure aligned with the center line of arm 22. In either position of adjustment bracket 21, web 20, and straightedge 2 may be swung upward about the hinge to overlie arm 22 in inoperative position, removing the scale from the drawing board surface.

I claim as my invention:

1. A perspective drafting machine comprising a straightedge, a straightedge arm supporting said straightedge, a mounting arm for said straightedge arm located at one side thereof, and control mechanism interconnecting said mounting arm and said straightedge arm, including a link connected to said straightedge arm and located at the side thereof opposite said mounting arm, means operable to maintain said link always parallel to said mounting arm, and a control link interconnecting said mounting arm and said first link and connected therebetween to said straightedge arm, and operable to maintain said straightedge directed at the vanishing point in various positions relative to said mounting arm.

2. A perspective drafting machine comprising supporting means, a wheel fixed on said supporting means, a control link pivoted for swinging about the axis of said wheel, a second link pivotally connected to said control link remote from said wheel, a second wheel fixed to said second link coaxially with the pivotal connection between said two links, means interconnecting said two wheels and operable to preserve corresponding angular relationship thereof, to maintain the direction of said second link constant in various swung positions of said control link, a straightedge, and a straightedge arm supporting said straightedge, pivotally connected to said second link, and pivotally connected to said control link intermediate said wheels for swinging relative thereto corresponding to swinging of said control link relative to said supporting means while maintaining said straightedge always directed at the vanishing point.

3. A perspective drafting machine comprising supporting means, a wheel fixed on said supporting means, a control link pivoted for swinging about the axis of said wheel, a second link pivotally connected to said control link remote from said wheel, a second wheel fixed to said second link coaxially with the pivotal connection between said two links, means interconnecting said two wheels and operable to preserve corresponding angular relationship thereof, to maintain the direction of said second link constant in various swung positions of said control link, a straightedge, a straightedge arm supporting said straightedge, pivotally connected to said second link, and pivotally connected to said control link intermediate said wheels for swinging relative thereto corresponding to swinging of said control link relative to said supporting means while maintaining said straightedge always directed at the vanishing point, and means operable to shift the position of the pivotal connection between said straightedge arm and said control link for altering the location of the vanishing point.

4. A perspective drafting machine comprising a mounting arm, a control link pivotally connected thereto, a wheel fixed relative to said mounting arm concentrically with the pivot axis of said control link, a second link pivoted upon

the end of said control link remote from said mounting arm, a second wheel fixed to said second link coaxially with the pivotal connection between said two links, belt means interconnecting said two wheels and operable to preserve corresponding angular relationship thereof, to maintain said second link parallel to said mounting arm in various swung positions of said control link, a straightedge, and a straightedge arm supporting said straightedge, pivotally connected to said second link, and pivotally and slidably connected to said control link intermediate said wheels for swinging relative thereto corresponding to swinging of said control link relative to said mounting arm and for lengthwise movement relative to said control link, to maintain said straightedge directed toward the vanishing point in all its positions.

5. The perspective drafting machine as defined in claim 4, and means supporting the mounting arm for swinging, thereby effecting bodily movement of the straightedge swung through an angle corresponding to the angle of swing of the mounting arm, to adjust angularly the position of the vanishing point toward which the straightedge is directed.

6. A perspective drafting machine as defined in claim 4, and a slide pivotally connected to the straightedge arm and slidably engaged with the control link for adjustment therealong to vary the distance between the vanishing point and the pivotal connection of the control link to the mounting arm.

7. A perspective drafting machine comprising a mounting arm, a control link above said mounting arm, pivotally connected thereto and including spaced upper and lower members, a wheel fixed relative to said mounting arm concentrically with the pivot axis of said control link and received between the upper and lower members thereof, a second link pivoted upon the end of said control link remote from said mounting arm, a second wheel fixed to said second link coaxially with the pivotal connection between said two links and received between the upper and lower members of said control link, belt means interconnecting said two wheels and operable to preserve corresponding angular relationship thereof, to maintain said second link parallel to said mounting arm in various swung positions of said control link, a straightedge, and a straightedge arm supporting said straightedge above said control link and pivotally connected to said two links for swinging relative thereto to opposite sides of said mounting arm corresponding to swinging of said control link relative to said mounting arm, to maintain said straightedge directed toward the vanishing point in all its positions at each side of said mounting arm.

8. A perspective drafting machine comprising a straightedge, an arm supporting said straightedge, mounting means for said arm, and control mechanism interconnecting said mounting means and said arm for swinging said arm relative to said mounting means, such control mechanism including a control link pivoted at one end on said mounting means for swinging across said mounting means from one side thereof to the other, a reference link pivotally connected at one end to said arm, means pivotally interconnecting the opposite end of said reference link to the swinging end of said control link for swinging of the interconnected ends of the two links across said arm from one side thereof to the other during swinging of said control link across said

mounting means, pivot means carried by said control link between the ends thereof, a longitudinal slide connection between said arm and said latter pivot means guiding said arm for sliding across said control link during swinging of said control link at opposite sides of and across said mounting means, and reference link orienting means interconnecting said mounting means and said reference link to maintain the latter constantly oriented relative to said mounting means during said swinging of said control link, thereby maintaining the straightedge directed toward a selected vanishing point in its various swung positions relative to said mounting means.

9. The perspective drafting machine defined in claim 8, and guide means on the control link for adjusting the position of the pivot means lengthwise thereof.

10. A perspective drafting machine comprising a straightedge, an arm supporting said straightedge, mounting means for said straightedge, and control mechanism interconnecting said arm and said mounting means for swinging of said arm relative to said mounting means while maintaining said straightedge directed at the vanishing point in all its swung positions, and including a link connected to said arm, a control link, means guiding said control link for swinging thereof across said mounting means from one side thereof to the other through a range, said control link crossing said arm and being pivotally connected thereto for swinging of said arm and longitudinal sliding thereof relative to said control link, pivot means interconnecting said first link and said control link at a location more remote from said mounting means than its crossing with said arm, and means interconnecting said mounting means and said first link for controlling orientation thereof.

11. In a perspective drafting machine, a straightedge, an arm supporting said straightedge, pivot means guiding said arm for swinging, means controlling swinging of said arm about said pivot means to dispose said straightedge, in various swung positions of said arm, directed toward a given vanishing point, and means, including a coupling element carried by the end of said arm and a complementary coupling element carried by the end of said straightedge, interconnecting said straightedge and said arm, said arm-carried coupling element having first straightedge supporting means disposed eccentrically of said arm and second straightedge supporting means disposed eccentrically of said arm to the side thereof opposite said first straightedge supporting means, and said complementary straightedge coupling element having means selectively engageable with said first straightedge supporting means to dispose an edge of said straightedge in precise alignment with the vanishing point with the straightedge disposed bodily on one side of the line of alignment, and further engageable with said second straightedge supporting means to dispose an edge of said straightedge in precise alignment with the vanishing point when the straightedge is disposed bodily on the opposite side of such line of alignment.

12. A perspective drafting machine comprising a mounting member, a control link pivotally connected to said mounting member for swinging freely through a substantial angular range, a second link pivotally connected to said control

link at a location spaced lengthwise on such control link from its pivot on said mounting member, to swing relative to the control link into and to either side of parallelism with said control link in a plane parallel to the latter's plane of swing relative to said mounting member and also thereby to be carried by said control link to be swung bodily thereby, control means including coordinated elements fixed to said second link and said mounting member, respectively, and maintaining said second link in fixed angular relation to said mounting member in various bodily swung positions of said second link carried by such control link, a straightedge arm, first means pivotally connecting said straightedge arm to said second link, second means spaced lengthwise of said straightedge arm from its first pivot and pivotally connecting said straightedge arm to said control link, said first and second pivotal connecting means supporting said straightedge arm in offset relation to said control link and second link on the same side of both thereof to swing through parallelism with such control link and second link without interference therefrom, one of said first and second pivotal connecting means including slide means permitting lengthwise sliding of said straightedge arm relative to its pivot in such pivotal connecting means, thereby to permit relative movement of said first and second pivotal connecting means toward and from each other during swinging of said second link and control link relative to each other throughout a range including and extending beyond opposite sides of the relative position of mutual parallelism of said control link, second link and straightedge arm, whereby said straightedge arm is maintained directed constantly at a fixed vanishing point throughout bodily swinging thereof with said control link and said second link, and a straightedge bodily carried by said straightedge arm.

13. The perspective drafting machine defined in claim 12, and means operable to adjust lengthwise of the control link the location thereon of the second means pivotally connecting the straightedge arm thereto.
